Attorney.

UNITED STATES PATENT OFFICE

WILLIAM L. SHARP, OF STEUBENVILLE, OHIO, ASSIGNOR TO THE OHIO FOUNDRY & MANUFACTURING COMPANY, OF STEUBENVILLE, OHIO, A CORPORATION OF OHIO

GAS HEATER

Application filed September 25, 1929. Serial No. 395,034.

My invention relates to gas heaters, and more particularly to stoves of the type which include a gas burner and clay elements for radiating heat of the burner flames.

5 In some types of stoves, lumps of burned clay or the like are placed loosely in front of and above radiants, such lumps being commonly termed artificial fuel and having the appearance of small lumps of coal, but 10 being of course incombustible. The loose arrangement of the lumps necessitates the employment of grate-like bars in front of the fuel and the radiants to hold the fuel in place, while it is sometimes difficult to effect the 15 proper distribution of the lumps over the radiants in order to produce a desired effect. Furthermore, the lumps frequently become lost.

One object of my invention is to provide a 20 structure wherein the artificial fuel is formed integrally with the radiants and which nevertheless produces a natural effect.

Another object of my invention is to provide an improved arrangement of radiants 25 wherein the passages for the gas flames are formed between the walls of adjacent radiants.

Still another object of my invention is to provide a heater of the character referred to 30 of generally simplified and improved form.

One form which my invention may take is shown in the accompanying drawing, wherein in Figure 1 is a front elevational view of the heater; Fig. 2 is a view taken on the line 35 II-II of Fig. 1; Fig. 3 is a sectional plan view of the heater, and Fig. 4 is a view taken on the line IV-IV of Fig. 2, on an enlarged scale. The heater shell or framework comprises a backwall 5, end walls 6 and a burner 40 plate 7 that are suitably secured together in any well-known manner and are supported on the usual feet or legs 8.

To the rear of the burner 9, a series of rectangular openings 11 are formed in the 45 plate 7. These openings 11 serve to receive rectangular extensions or lugs 13 formed on the lower ends of clay radiants 15, to support such radiants against displacement.

The radiants 15 are provided with inter- 50 fitting tongues and grooves 16 and 17, as

shown more clearly in Fig. 4, to maintain them in proper relative alinement. The rear or body portions of the radiants not only have the interfitting tongue and groove arrangement but are thickened to such extent 55 that they serve as a backwall. The web portions 18 of the radiants are of reduced width and provided with small projections 19 which become highly heated by the flames from the burner 9 and facilitate the radiation of heat. 60 The portions 18 are spaced apart such distance that vertical passages for the flames are provided between the various radiants, as distinguished from the common practice of making the radiants or burner tubes hollow 65 and effecting radiation through reticulated openings formed in such tubes.

Irregularly-shaped lugs 20 are formed integrally with the radiants 15 and constitute the front faces thereof. These portions 20 70 are colored to give them the appearance of fuel. The irregular shape of the elements 20 permit the radiation of heat therebetween and they will become heated to an extent that they will have the appearance of glowing 75 coals. Furthermore, they are of such size relative to the web-like portions 18 of the radiants that such portions 18 are largely concealed and the elements 20 have the appearance of loosely piled fuel. If desired, 80 additional lumps of fuel may be loosely piled upon the uppermost elements 20.

In order to further maintain the radiants 15 in place, I provide holes therein for the reception of a tie rod 22 which extends 85 through the radiants and through the end walls 6 of the heater. By removing one of the nuts on the ends of the rod 22 it may be slid out of place to permit removal of the radiants.

From the foregoing it will be seen that I not only provide a heater of the artificial fuel type wherein the artificial elements are rigidly maintained in place, but an improved type of radiant which need not be made hollow 95 and consequently of delicate structure as in the case of ordinary burner tubes, the passages for the gas flames being provided between the various radiants as above explained. Furthermore, the radiants are se- 100

surely held against displacement either with respect to one another or with respect to the frame of the stove.

I claim as my invention:—

- 5 1. A gas heater comprising a supporting framework, a burner extending across said framework, and radiants mounted on said framework above the burner, those portions of the radiants immediately above the burner being of reduced thickness in a direction longitudinally of the burner, to provide vertical gas passages between the radiants.
- 10 2. A gas heater comprising a supporting framework, a burner extending across said framework, and radiants mounted on said framework above the burner, those portions of the radiants immediately above the burner being of reduced thickness in a direction longitudinally of the burner, to provide vertical gas 15 passages between the radiants, and the radiants having irregularly-shaped protuberances upon their front faces and forwardly of said reduced portions.
- 20 3. A gas heater comprising a supporting framework, a burner extending across said framework, radiants mounted on said framework above the burner, those portions of the radiants immediately above the burner being of reduced thickness in a direction longitudinally of the burner, to provide vertical gas 25 passages between the radiants, and radiating tips carried by the radiants and extending into the said passageways.
- 30 4. Heater structure comprising a supporting frame, radiants carried by said frame in side-by-side relation, means between the sides of the radiants for effecting interlocking thereof, and means on said radiants for effecting interlocking engagement with the frame-work.
- 35 5. The combination with a heater, of a plurality of radiants therefor each having artificial fuel elements formed on the front sides thereof, the said elements being connected to their respective bodies by portions of reduced width and such portions of reduced width being spaced apart to provide gas passages.
- 40 6. The combination with a heater, of a radiant therefor having artificial fuel elements formed on the front side thereof, the said elements being connected to the body portion of the radiant through a reduced portion thereof.
- 45 7. The combination with a heater of a radiant therefor having an upwardly-extending portion and a portion extending in a direction generally transverse to the first-named portion, and artificial fuel elements formed on the exposed sides of said element.
- 50 8. Heater structure comprising a framework, and clay elements supported by said framework, the rear portions of said clay elements being of sufficient thickness that they together form a backwall and the front portions thereof being spaced apart and of re-

duced horizontal dimension in order to function as radiants.

9. Heater structure comprising a framework, clay elements for said framework having enlarged rear portions which together serve as a backwall and having reduced intermediate portions spaced apart to function as burner tubes and also having enlarged protuberances extending outwardly from said reduced portions.

10. Heater structure comprising a framework including a burner plate having a burner opening therein, clay elements supported by said framework and plate, the rear portions of said elements being of sufficient thickness that they together form a backwall, and the front portions thereof being spaced apart and of reduced horizontal dimensions in order to function as radiants, and means for effecting interlocking engagement between each of the lower ends of the thickened portions of said elements and the plate.

11. Heater structure comprising a framework including a burner plate having a burner opening therein, and a series of openings disposed rearwardly of the burner opening, clay elements supported on said burner plate and having protuberances extending into the said series of openings and forwardly extending projections disposed over the burner opening.

12. Heater structure comprising a framework having a burner plate, a burner disposed below said plate adjacent to the forward edge thereof, clay elements disposed in side-by-side relation upon said burner plate and having forwardly extending projections disposed above the burner, and means for effecting interlocking engagement between the lower ends of said elements and the burner plate at points rearwardly of the burner.

In testimony whereof I, the said WILLIAM L. SHARP, have hereunto set my hand.

WILLIAM L. SHARP.
